UNITED STATES PATENT OFFICE.

LOUIS BOFIRD, OF NEW YORK, N. Y.

SWINGING SLIDING WINDOW-SASH.

No. 918,270.

Specification of Letters Patent. Patented April 13, 1909.

Application filed June 1, 1908. Serial No. 436,161.

To all whom it may concern:

Be it known that I, LOUIS BOFIRD, a citizen of the United States, residing at New York city, in the county of New York and 5 State of New York, have invented certain new and useful improvements in Swinging Sliding Window-Sashes, of which the following is a specification.

This invention relates to sliding swinging 10 window sashes and has for its object the improvement therein of certain details whereby the swinging sash may be more easily manipulated and whereby the swinging of the sash may not only be more easily effected, but 15 may be done without the wear and tear incident to the manipulation of such as they are now constructed.

With these objects in view and in view of others, which will later appear, the invention 20 consists in the structure of parts and in the combination thereof substantially as herein shown, described and claimed.

In the accompanying drawing, which forms a part of this specification, Figure 1 represents in elevation a two sash window equipped with my improvement; Fig. 2 is a side elevation of a window frame, in which are mounted two sashes equipped with my improvement, said sashes being shown 30 swung into horizontal position and the upper sash slid down near the lower one; Fig. 3 is a detail view on an enlarged scale disclosing features of my invention; Fig. 4 is a detail view on a still larger scale showing my improved pivot and the manner in which it is located in place; Fig. 5 represents in side view the handle of the pivot; Fig. 6 an end view of the same; Fig. 7 an edge view of one of the journal plates; and Fig. 8 represents, 40 on an enlarged scale, a section through one side of the sash and the adjacent stile.

The principal feature of this improvement in sliding swing sash resides in the mechanism by which provision is made for easing off 45 the sash from the sliding stiles before attempting to swing the sash. This is an essential improvement because in most swinging sash heretofore constructed, the swinging of the sash caused a shearing action between 50 the grooves and coöoperating beads in the joints between the sash and stiles. This shearing action rapidly wears away these parts and soon causes a loose fit between the sash and the stiles and also produces frayed 55 edges on the sash. In the present invention these objections are overcome by the form

and structure adopted for the pivots upon which the sash swings.

In the drawings 7 indicates a window frame, the jambs of which appear in section 60 at 8 in Fig. 3, 9 represents the upper sash and 10 the lower sash of the window shown.

11 represents the left-hand stile and 12 the right-hand stile, to which the sash 10 is pivoted.

13 indicates the sash cords for the upper sash, the same being connected in any suitable way to the stiles 11 and 12.

The joint between the stiles and the sash is preferably made as indicated in Fig. 6, 70 wherein the sash is shown as grooved and the stile is shown as having thereon a single bead fitting said groove. The stiles are pressed toward the sash by suitable springs located between them and the jambs. In the drawing these springs are indicated at 14 as simple plate springs. The pivot, on which the sash swings is indicated at 15 and is provided with a lever or handle 16. In the preferred manner for mounting the pivot a journal plate, 75 17, is let into the stile and a like plate 18 is let into the sash at the inner edge thereof. A hole is bored through the sash of a larger diameter than the pivot so that a spring, as 19, may be located about the pivot between 80 the plates 17 and 18. The outer end of the pivot 15 is upset or riveted against the outer edge of the plate 17. The spring 19 tends to force the plate 17 and its stile 12 away from the plate 18 and its sash. The handle 16 of 85 the pivot may be provided with any suitable cam surface, such for instance, as that indicated at 20 in Figs. 4 and 5, which, on engagement with the plate 18, will force the stile and sash together. When the cam 20 is 90 swung away from the sash, as indicated at the left in Fig. 3, then the spring 15 expands and forces the stile away from the sash. At the right in Fig. 3, the cam is shown as engaging the sash in the same manner as in 100 Fig. 4, thereby holding the stile to the sash. The springs 19 are made just enough stronger than the springs 14 to provide for creating a sufficient clearance between the sash and stiles, that is, to disengage the beads from 105 the grooves when the cams are swung away from the sash thereby permitting of easy swinging of the sash and preventing the wearing away of the edges of the grooves against the beads as the sash is swung. This 110 mode of uniting the stiles with the sash and of providing a clearance between them also

avoids the extra trouble and expense incident to protecting the meeting edges between stiles and sash with metallic strips that has been necessary in many forms of 5 swinging sashes heretofore constructed. The cam or wedging pivots, as those described may be called, also provide for making a positively tight joint between the stiles and the sashes when the latter are in vertical 10 position.

The invention claimed is:—

1. The combination with a sash, of sliding stiles at the sides thereof, the meeting edges of said sash and stiles being fitted together 15 by a bead and groove joint, a journal plate let into the face of each stile midway of its length, a journal plate let into each side rail of the sash midway of its length and at the inner edge thereof, a horizontal pivot located 20 in each pair of said journal plates and provided with a head at the outer edge of the journal plate in its respective stile and with a cam handle at right angles to the pivot at the inner edge of the journal plate in its re-

spective side rail for engagement with said 25 plate for the purpose set forth, and a spring located about each pivot between the journal plates, substantially as and for the purpose set forth.

2. A pivoting fixture for sliding swinging 30 window sashes, consisting of a pair of journal plates, a pivot mounted therein and headed at one end against the outermost of said plates and provided at its opposite end with a cam handle at the inner edge of the other 35 journal plate, and a spiral spring located about the pivot between the inner edges of said plates, said handle being integral with the pivot and at right angle thereto and the cam surface thereof being adapted to engage 40 the edge of the adjacent journal plate and thereby draw said plates toward one another in opposition to said spring, substantially as and for the purpose set forth.
